UNITED STATES PATENT OFFICE.

STANISLAUS KRAUSE AND STEFAN GRUDZINSKI, OF ZURICH,
SWITZERLAND.

COIN-FREED ALARM-CLOCK.

SPECIFICATION forming part of Letters Patent No. 794,718, dated July 18, 1905.

Application filed November 4, 1904. Serial No. 231,434.

To all whom it may concern:

Be it known that we, STANISLAUS KRAUSE and STEFAN GRUDZINSKI, engineering students, citizens of the Swiss Republic, residing at Zurich, Switzerland, have invented certain new and useful Improvements in Coin-Freed Alarm-Clocks, of which the following is a specification.

This invention relates to a device for use with alarm-clocks for operating the latter by the insertion of a coin, assuming the springs of said clocks to be in a wound condition. The person who desires to use such clock must before inserting the coin arrange the hands to indicate the correct time and also adjust the alarm for the time at which it is desired it shall strike. After so adjusting the alarm and inserting the coin the clockwork itself is automatically started.

A form of construction of the improved clock is shown as an example in the annexed drawings, in which the clockwork is shown diagrammatically and only in part and the clock-casing is not illustrated.

Figure 1 is a side elevation; Fig. 2, a plan view. Figs. 3 and 4 are end views from the left and right, respectively; and Figs. 5 and 6 are sectional detail views.

Between the clockwork, which is of known construction, and the front wall of the casing a partition a is arranged, consisting of the plates a' and a'' and the distance piece or pieces a''' . (In Fig. 1 the plate a' is assumed to be removed.) In this partition a is the passage or channel b for the coin, said passage terminating at the front wall of the casing, and below the opening for insertion of the coin there is arranged between the plates a' and a'' the double-armed lever c , pivoted at c' . This lever can be counterbalanced by means of a weight d on the end thereof and is held by said weight in its position of rest against a stop-pin e^2 , Fig. 1. At its lower end the coin-passage is closed by the double-armed lever e , pivoted at e' between the plates a' and a'' . The said lever e is held in its position of rest against a pin e^2 . On the shorter arm of said lever two stop-pins e^3 and e^4 are arranged, one of which, e^3 , is adapted to hold the balance f of

the clockwork in its position of rest, whereas the other pin e^4 is adapted to stop the alarm-work. For this purpose on the axle g , on which is mounted the alarm-striker g' , is arranged a lever g'' , which can be completely displaced only when the stop-pin e^4 is raised—that is to say, when said pin is in the path of the recess or bend g^3 in said lever g'' . On the longer arm of the lever e is arranged a pin e^5 , which passes through a slot a^4 in the partition-plate a' and engages the bifurcated end of the double-armed lever h , pivoted at h' . The upper arm of said lever h bears against a spring i , secured to the plate a' .

The pin i' , fixed to the spring i , Figs. 2 and 4, is adapted to momentarily stop the lever c .

On the back plate of the clock-frame is pivotally suspended at k' the lever k , having arms k^2 and k^3 passing through slots a^5 and a^6 , respectively, in the partition a . This lever is for the purpose of successively arresting and releasing the coins and is operated by means of an abutment m , arranged on the spring-wheel l of the alarm-work and is acted upon by a spring n , fixed to the back plate.

The action of the device is as follows: The coin inserted encounters the longer arm of the lever c , pressing it downward into the position shown in broken lines in Fig. 1, and rolls downward through the channel or passage b onto the longer arm of the lever e , also pressing this latter lever down into the position shown in broken lines in Fig. 1. At the same time the pin e^3 acts upon the lever h and causes it to rock on its pivot h' , so that its upper end presses the spring i toward the partition a . The pin i' is thus caused to pass through a suitable slot in said partition a to prevent the lever c , which is now in its upper position, from being again depressed. The coin is temporarily prevented by the arm k^2 of the lever k from leaving the lever e . (See Figs. 2, 4, and 5.) The said lever e remains in the position given to it by the coin—that is, with the shorter arm thereof raised—so that the stop-pin e^3 is removed from the balance f of the clockwork and the latter can begin its movement. When at the predetermined moment the alarm-work is released, the spring-

wheel l , with the abutment m , passes the bend k^4 of the lever k , and the latter is pressed back so that its arm k^2 is removed from the slot a^5 in the plate a^2 , and simultaneously the arm k^3 enters the slot a^6 , Fig. 6. The coin can then pass farther along the lever e until it encounters the arm k^3 . When the abutment m has again released the lever k , the latter is returned to its original position by the spring n , and with it also the arms k^2 and k^3 . The coin is thus released and can be guided into a suitable cash-drawer. (Not shown.) As soon as the coin has thus passed along the lever e returns to its former position—that is to say, its shorter arm falls again, the stop-pin e^3 stops the balance f , and the stop-pin e^4 does not permit the lever g^2 to completely oscillate, so that both the alarm-work and clockwork are stopped at the same time.

Should a second coin be inadvertently inserted when the clockwork is in action, said coin will roll along the lever c (which is arrested by the pin i') toward the passage o , leading to outside the clock-casing. The same thing takes place with coins which are not of sufficient weight to depress the lever c .

This alarm-clock is especially suitable for hotels, as it enables every visitor to be awakened at the hour he desires by paying a small fee.

We claim—

1. In a clock the combination with a clock-work and alarm-work, of a chute for passage of a coin, a lever normally stopping the clock and alarm works and adapted to be depressed by the coin to release the clockwork, and means operated by the alarm-work adapted to arrest the coin until the alarm has operated and thereupon to release said coin to allow said lever to rise again to stop the clockwork, substantially as described.

2. In a clock the combination with a clock-work and alarm-work, of a chute for passage of a coin, a lever adapted to be depressed by the coin, a second lever normally stopping the clock and alarm works and also adapted to be

depressed by the coin to release the clock-work, and means operated by the alarm-work adapted to arrest the coin until the alarm has operated and thereupon to release said coin to again stop the clockwork, substantially as described. 50

3. In a clock the combination with a clock-work and alarm-work, of a chute for passage of a coin, a counterbalanced lever adapted to be depressed by the coin, a second lever normally stopping the clock and alarm works and also adapted to be depressed by the coin to release the clockwork, a suspended lever operated by the alarm - work and having arms adapted to arrest the coin until the alarm has 60 operated and thereupon to release said coin to again stop the clockwork, and means for preventing the depression of the counterweighted lever during the operation of the clockwork substantially as described. 65

4. In a clock the combination with a clock-work and alarm-work, of a chute for passage of a coin, a counterbalanced lever c adapted to be depressed by the coin, a second lever normally stopping the clock and alarm works 70 and also adapted to be depressed by the coin to release the clockwork, a suspended lever operated by the alarm-work and having arms adapted to arrest the coin until the alarm has operated and thereupon to release said coin to again stop the clockwork, a third double-armed lever h operated by the lever e , a spring acted upon by said lever h and an abutment on said spring adapted to prevent the depression of the first-mentioned lever c during the 80 operation of the clockwork substantially as described.

In witness whereof we have signed this specification in the presence of two witnesses.

STANISLAUS KRAUSE.
STEFAN GRUDZINSKI.
